DESIGN FOR A COMBINED AIR DISTRIBUTING AND ILLUMINATING DEVICE

Franz J. Kurth and Ladislav Fischer, New York,
N. Y., assignors to Anemostat Corporation of America, a corporation of Delaware

Application September 12, 1939, Serial No. 87,160

Term of patent 14 years

To all whom it may concern:

Be it known that we, Franz J. Kurth and Ladislav Fischer, citizens, respectively, of Germany and the United States, residing at New York city, in the county of New York and State of New York, have invented a new, original, and ornamental Design for a Combined Air Distributing and Illuminating Device, of which the following is a specification, reference being had to the accompanying drawing, forming part thereof and wherein:

We claim:

The ornamental design for a combined air distributing and illuminating device, as shown.
